UNITED STATES PATENT OFFICE.

LOUIS NOEL, OF NEW YORK, N. Y.

DESIGN FOR A BRACELET.

Application filed October 28, 1922. Serial No. 4,151. Term of patent 3½ years.

To all whom it may concern:

Be it known that I, LOUIS NOEL, a citizen of France, and a resident of the city of New York, borough of Manhattan, in the county and State of New York, United States of America, have invented a new, original, and ornamental Design for a Bracelet, of which the following is a specification, reference being had to the accompanying drawings, forming part thereof.

That portion of the bracelet showing the complete ornamentation in Figure 2 extends the entire length of the bracelet.

I claim:

The ornamental design for a bracelet, as shown.

LOUIS NOEL.
